UNITED STATES PATENT OFFICE

GEORGIE BEATRICE CAMPBELL-ROSS, OF ROUND LAKE, ILLINOIS

PLAITING IRON

Application filed April 23, 1928. Serial No. 271,996.

The invention relates to plaiting irons.

In plaiting garments, it is frequently desired to form plaits of different shapes or designs. One object of the invention is to provide an iron in which the plaiting member carried thereby is readily changeable to adapt the iron for forming plaits of different shapes or designs. Another object of the invention is to provide an improved plaiting iron in which provision is made for conveniently and readily changing the plaiting member carried by the iron, and in which the changeable plaiting members will be firmly held against the body of the iron for heat transference thereto.

The invention consists in the several novel features hereinafter set forth and more particularly defined by the claims at the conclusion hereof.

20 In the drawing: Fig. 1 is a perspective of a plaiting iron embodying the invention. Fig. 2 is a perspective of the plaiting member detached from the body of the iron. Fig. 3 is a detail perspective of a portion of the body of the iron. Figs. 4, 5 and 6 are sectional views, illustrating plaiting members adapted to be attached to the iron and for different kinds of plaiting and associated plates for said members respectively. Fig. 30 7 is a detail of a plate for the plaiting of another design.

The invention is exemplified in an electrically heated iron comprising a body 8 which contains a resistance element (not shown), as well understood in the art, a top 9 fixedly secured to said body, a U-shaped handle frame 10 secured by screws 11 to the top 9 and a handle 12 secured in the upper end of said frame. A socket 13 for a switch plug on a flexible cord is provided at one end of the iron-body. A thumb-rest 14 is secured at one side of the handle frame 10. Feet 15 and 16 are provided at one end of the body to permit the iron to be stood on end when desired. The body 8 is formed of metal and comprises a semi-cylindrical lower portion 8^a and approximately parallel sides 8^b extending from said curved portion to the top 9.

45 A plaiting member, adapted to be attached to the body 8 and to snugly fit around its

55 sides and curved bottom, consists of a metal member 17. Said member comprises a bottom portion 17^a which has its inner periphery cylindrical to fit snugly against and conform to the curved bottom 8^a of the iron-body 8 and sides 17^b which have their inner faces smooth and conform substantially to the sides 8^b of the iron body 8. The outer face of the sides 17^b and curved bottom 17^a are formed with corrugations or flutes 18 which 60 extend from end to end of the member 17.

65 The plaiting member 17 is removably held in its operative position by means of a device which is mounted on the top 9 and cooperates with a pair of lugs or ears 19. The latter are formed integrally with and project upwardly from the sides 17^b of the plaiting member. The aforementioned device comprises a pair of locking members 20 which are slidably mounted at the sides of the top 70 9 so that they may be shifted outwardly into sockets or recesses 21 which are formed in the central portions of the lugs 19. Straps or brackets 22 are employed to guide the locking members. The latter are provided with 75 stop lugs 20^a which operate to prevent them from being displaced with respect to said brackets. A T-shaped finger lever 23 is pivotally connected, as at 24, to the inner end of one of the locking members and is pivotally connected to the inner end of the other member by a link 25. By pressing the finger button 23^a of this lever downwardly, the locking members will be shifted inwardly and out of engagement with the recesses 21 so that 80 the plaiting member 17 is free to be withdrawn. Springs 26 are connected to the brackets 22 and to the locking members and are operative to shift the latter outwardly 85 into engagement with the recesses 21. A 90 characteristic of disposing the locking device on the top of the iron is that it may be readily manipulated by the user of the iron and does not become heated by the body 8. The resilient engagement between the sides of the member 17 and the sides of the iron-body results in firmly holding the member on the body for efficient heat transference to the plaiting member from the body which contains the heating or resistance element. This 95 100

construction exemplifies a detachable plaiting member or plate which may be readily secured in its operative position and detached from the body when the device is operated to shift the locking members 20 inwardly. The 5 plaiting member 17 is adapted to coact with a flat plate 27 which is provided with flutes or grooves 27^a on its upper face which conform to the flutes or grooves 18 of the member 17.

10 In operation, the iron, with the member 17 locked thereon, will be placed so that the ribs on said member will interfit with the ribs on the plate 27 after the material to be plaited has been laid over the plate. The iron will 15 then be manipulated by transverse rocking and endwise sliding, if desired, to heat the material from the body and to impress plaits thereon conformably to the shape of the flutes or grooves formed in the member 17 and 20 plate 27.

15 In practice, it has been found desirable to have an available equipment for the plaitings of different shapes or designs, and for that purpose, provision is made for ready attachment and detachment of the member 17 from 25 the iron 8. Fig. 4 illustrates a member 17^a similar to member 17 and similarly attachable to and detachable from the body 8 of the iron, except that it is formed with alternating 30 ribs 28 and intermediate grooves with sharp connecting corners to form what are generally known as box-plaits in the material. 27^a is a plate with ribs and grooves 28^a conforming to the ribs and grooves on the member 17^a and adapted to coact with said member 35 for forming box-plaits in the fabric.

40 Fig. 5 illustrates a member 17^e which is similar in construction to the member 17 and similarly adapted to be attached to and detached from the body 8 and which is provided with V-shaped ribs 29 to form what is generally designated as accordion plaits in the material. The flat plate 27^e has ribs 29^a 45 conforming to the ribs 29 of member 17^e and is adapted to coact with member 17^e to form accordion plaits in the fabric.

45 Fig. 6 illustrates a member 17^f which is similar in construction to the member 17 and is similarly attachable to and detachable from the body 8 and is provided with longitudinal ribs 30 which are of the shape adapted to 50 form what is generally known as knife-edge plaits in the fabric or material. A flat plate 27^b is provided with teeth 30^a conformably to 55 the teeth 30 on the member 17^f and is adapted to coact therewith to form knife-edge plaits on the material.

60 Fig. 7 illustrates a flat plate 27^g which is provided with V-shaped ribs which diverge and are of gradually increasing width from a common point, conforming to the configuration known as "sunburst" plaiting which is 65 adapted to coact with a member like 17, but having a corresponding configuration on its

outside face, so that when the member 17, attached to and heated by the body 8, is manipulated over the plate 27^g, the material will be impressed with "sunburst" plaits.

65 The invention exemplifies a plaiting-iron 70 which is adapted for different kinds of plaiting, and in which the plaiting member carried by the iron may be readily attached to and detached from the iron-body. In order to provide an equipment for substantially all 75 of the kinds of plaiting ordinarily desired, it is only necessary to provide one electrically heated iron and the detachable plaiting members and coacting plates adapted for different 80 kinds of plaiting or designs. Besides providing for ready removal and replacement of the plaiting member, its resiliency results in efficient contact and heat transference between the body of the iron which contains the heating element and the plaiting member carried thereby.

85 The invention is not to be understood as restricted to the details set forth, since these may be modified within the scope of the appended claims, without departing from the 90 spirit and scope of the invention.

95 Having thus described the invention, what I claim as new and desire to secure by Letters Patent, is:

1. A plaiting iron comprising in combination, a body embodying a semi-cylindrical bottom and substantially parallel sides, a handle secured fixedly to the body, and a member formed separately from and removably connected to the body and consisting of 100 a bottom part curved transversely and so as to fit against the body-bottom, and parallel side parts for lapsing the sides of the body, the outer faces of the bottom and side parts of said member being fluted, and adapted to 105 form plaits in conjunction with a correspondingly fluted plate and when the body and member are rocked sidewise over such plate.

110 2. A plaiting iron comprising in combination, a body, a handle secured fixedly to the body, a member formed separately from and adapted to extend around the body and consisting of side parts and a transversely curved bottom part, the outer faces of said sides and bottom being fluted and adapted to 115 form plaits in conjunction with a correspondingly fluted plate and when the body and member are rocked sidewise over such plate, and a connection for attaching the member to the body comprising apertured 120 lugs on the side parts of the member and elements slidably mounted on the body and shiftable into the apertures in the lugs.

125 Signed at Chicago, Illinois, this 10th day of April, 1928.

GEORGIE BEATRICE CAMPBELL-ROSS.
